CLAIM

The ornamental design for the combined computer keyboard and mouse pad drawer, as shown and described.

DESCRIPTION

FIG. 1 is an isometric view of a combined computer keyboard and mouse pad drawer showing my new design;

FIG. 2 is a left side elevational view thereof, the right side being a mirror image;

FIG. 3 is a right side cross-sectional view thereof, taken on line 3—3 of FIG. 1;

FIG. 4 is a front elevational view thereof;

FIG. 5 is a top plan view thereof;

FIG. 6 is a rear elevational view thereof;

FIG. 7 is a bottom plan view thereof; and,

FIG. 8 is a left side cross-sectional view thereof, taken on line 8—8 of FIG. 1.
